JOSEPH THOMAS PARLOUR, OF BROOKLYN, NEW YORK

Letters Patent No. 65,691, dated Jun. 11, 1867

IMPROVED KEEL-BLOCK OR REST.

The Schedule referred to in these Letters Patent and making part of the same.

TO ALL WHOM IT MAY CONCERN:

Be it known that I, JOSEPH T. PARLOUR, of Brooklyn, Kings county, New York, have invented a new and improved Block or Support for Keels to Vessels; and I do hereby declare that the following is a full, clear, and exact description thereof, which will enable others skilled in the art to make and use the same, reference being had to the accompanying drawings forming part of this specification.

The present invention relates to a new and improved construction of the blocks or rests or supports employed for the keels of vessels, when hauled or run into the docks for repairs, which construction is of such a nature, that without necessarily descending into the dock, or even pumping or otherwise removing the water therefrom, the several blocks, whether one or more, can be adjusted to the proper heights to accommodate the draught of the vessel whether large or small. In the accompanying plate of drawings my improved block or support for keels to vessels is illustrated—

Figure 1 being an elevation of one side of the same; and

Figure 2, a central vertical section taken in the direction of the length of the block.

A, in the drawings, represents a keel-block, made according to the present invention, and in three parts or sections B, C, and D, which are placed one above and on top of the other, with the lower one, D, of the series resting upon the upper side of a block, E, fixed in position in and to the bottom of the dock. The upper edge or side of block E has two parallel raised ribs, extending in the direction of its length, on which raised ribs, and guided by the same, the under side of the lower block section D is arranged to be moved or slid. The upper side of the lower block section is made of a taper or wedge shape from end to end. The under side of the section block C is also made of a taper or inclined shape, corresponding to that of the lower block, and both are suitably constructed upon their surfaces in contact with each other, to move and slide one upon another in the direction of their length. The upper side of the block section C is horizontal or level in position, and on this rests the parallel and upper block section B of the keel-block, this upper block section constituting that portion of the keel-block with which the keel of the vessel comes in direct contact or on which it directly rests. To one side of the upper block section the upper ends of vertical rods L are secured, which rods, extending down upon the same side of the keel-block, pass through vertical guide-tubes or passages M suitably located therefor, and by means of which the said block section is guided in a straight and direct vertical line or direction as it rises or lowers, or is lifted or allowed to fall, according as the wedge-shaped block sections are moved in or toward or drawn outward from and beneath the upper block section. To operate or draw the wedge-shaped block sections out, as above stated, cords or ropes N are hung to the eye-bolts O at the larger ends of each of the same, by which ropes, if suitably passed or run over pulleys to the top of the dock in which the keel block is located, it is plainly apparent that the top of the said block, by properly pulling such ropes, can be readily, easily, and with no trouble lowered to the proper height or distance from the bottom of the dock to accommodate the draught of the vessel which may have been hauled or run into the same, without necessarily descending into the dock, or pumping, or otherwise removing the water therefrom. To draw in the wedge-shaped sections, a rope, P, is provided for the upper one of the two sections, to which it is suitably hung therefor, and a rope, Q, for the lower section. R, a ratchet-bar secured to lower block section along its upper edge, with the teeth of which ratchet-bar R a pawl, S, on the upper block section, engages, and thus serves to hold the said upper section from sliding or moving after being once set; this pawl being hung to a rock-lever or arm, T, hung to and upon the inside of the upper block section, and provided with ropes at each end, that, being passed to the top of the dock, enable such pawl to be properly operated for setting the block section free, or fixing or holding them in position. It may be here observed that it is intended to combine with the lower section of the block a suitable arrangement of pawl and ratchet-bar to enable it to be fixed or held in position, or set free for being moved.

Having thus described my invention, I claim as new, and desire to secure by Letters Patent—

1. A block or support for the keel of a vessel, etc., when made in separate parts or sections, constructed and arranged together so as to be operated substantially as and for the purpose described.
2. The upper or cap section B of a keel-block, so arranged that as it is raised or lowered it will move and be guided in a vertical plane or direction, substantially as described.
